UNITED STATES PATENT OFFICE

ROBERT HERMANN MEVES, OF BERLIN-FRIEDENAU, GERMANY

LETTER FILE

Application filed September 27, 1930, Serial No. 484,816, and in Germany September 28, 1929.

This invention relates to a letter file of the kind comprising filing pins secured by means of a supporting base to a cover which is also provided with a latch plate adapted to receive 5 and interlock with the free ends of the pins, and the invention consists in the provision of a pair of transfer arches mounted on a supporting base which is capable of being detachably secured to the supporting base of 10 the filing pins with the arches in position to form continuations of the pins.

Fig. 1 of the accompanying drawing represents an end view of a letter file according to the invention,

15 Fig. 2 is a top view thereof showing the two supporting bases separated from each other,

Fig. 3 is an end view of a modified construction,

20 Fig. 4 is a top view of the latter showing the two supporting bases separated from each other,

Fig. 5 is an end view of a further modification of the file,

25 Fig. 6 is a top view of the latter modification,

Fig. 7 is a perspective view of the file without the transfer arches,

30 Fig. 8 is a plan view of a latch used in the device, and

Fig. 9 is a longitudinal section of said latch.

The file comprises a pair of filing pins 3 and 3' secured by means of a supporting base 35 1 to a file cover 27. The latter also carries, as shown in Fig. 7, a latch plate 24 having apertures 21 and 21' for the reception of the free ends of the filing pins. Latches 22, controlled by a spring 25 and fitted with an operating handle 26, are adapted to snap into 40 notches 23 in the pins for locking the latter to the plate 24. This is the normal position of the filing pins.

To facilitate the insertion of letters in their 45 proper positions in the file, a pair of transfer arches 4 is provided, the supporting base 2 of which is adapted to be detachably secured to the base 2 with the arches in position to form continuations of the pins 3, 3', as best shown in Fig. 5. The transfer arches are hinged to

the base 2 and controlled by an operating handle 31.

For the convenient connection of the two supporting bases, the latter may be constructed in various manners. In the construction according to Figs. 1 and 2 the base 1 has the form of a plate which is doubled upon itself to form lips between which a tongue 29 on the base 2 can be inserted. The tongue 29 is formed with corrugations 8, 8' adapted to inter-engage with correspondingly corrugated lip portions 5, 5' on the base 1. The two supporting bases are slid into connection with each other in the longitudinal direction of the corrugations. The tongue 29 has also a wart 9 which, on the two parts being slid into connection with each other, snaps into engagement with an aperture 7 made in a resilient lug 6 on the supporting base 1 and thus retains the elements in their proper relative positions.

In the constructions shown in Figs. 3 to 6, the supporting base for the filing pins is composed of two plates 1' and 1'' the former of which carries the pins while the latter is secured to the cover 27. The two plates are connected together by means of hinges 28 which allow the filing pins to be turned, in the absence of the transfer arches, from a horizontal into a vertical position, while the cover 27 remains flat on its support.

For connecting the two supporting bases together, the base 2' in Figs. 3 and 4 is formed with a tongue 10 which is inserted between the two plates 1' and 1'' and between lateral positioning lugs 14 and 14' which are stamped out from the plate 1'. As the parts are pushed together, resilient corrugated blades 11 and 11' on the tongue 10, snap into engagement with ridges 13 and 13' on the plate 1' for retaining the elements in connected position.

In the arrangement according to Figs. 5 and 6, the supporting base 2'' is fitted with two pivoted catches 18 and 18' which are controlled by a spring 17 and which are provided with nose pieces 30 which pass through and snap into engagement with looped brackets 19 and 19' on the plate 1'. The catches have the form of double-armed levers the

outer ends 20 of which are bent up for manual operation. The relative positioning of the two supporting bases is effected by means of a tongue 15 on the base 2" which fits in a corresponding recess 16 in the plate 1'.

I claim:

1. In a letter file of the character described, the combination with a file cover of a pair of filing pins, a supporting base for said pins secured to the cover, a latch plate secured to the cover for the reception of the free ends of the filing pins, a pair of transfer arches, a supporting base for said arches, and means for detachably securing said latter supporting base to that of the filing pins with the transfer arches in position to form continuations of said pins.
- 10 2. A structure as claimed in claim 1 wherein in the means for securing the two supporting bases to each other comprises a tongue on one base and lips on the other base adapted to receive said tongue between them, said lips and tongue being formed with corrugations adapted to inter-engage for maintaining the connection.
- 15 3. A structure as claimed in claim 1 wherein in the means for securing the two supporting bases together comprises a tongue on one base adapted to engage in a recess in the other base, a pair of pivoted, spring-controlled catches on one base, and a pair of brackets on the other base adapted to interengage with said catches.
- 20 4. A structure as claimed in claim 1 wherein in the supporting base for the filing pins comprises two hingedly connected plates one of which is connected to the cover while the other carries the pins.

40 ROBERT HERMANN MEVES.
